UNITED STATES PATENT OFFICE

2,479,851

DELAYED ARMING DEVICE FOR
PROJECTILES

James F. McCaslin, Cleveland, Ohio, and Jean Fink, Delavan, Wis.; said Fink assignor to The George W. Borg Corporation, Chicago, Ill., a corporation of Delaware

Application May 6, 1947, Serial No. 746,298

13 Claims. (Cl. 102—79)

1

This invention relates to delay arming devices forming parts of the booster charge of a projectile fuse and which are interposed between the fuse and booster charge to prevent a premature detonation of the latter upon premature functioning of the former.

An object of the invention is to provide a delay arming device which is an improvement over that disclosed in the co-pending application of James F. McCaslin, Serial No. 588,879, filed April 17, 1945, now Patent Number 2,446,545, granted August 10, 1948.

A further object is to provide a pivotal unit including a gear train and escapement wherein the escapement is normally positioned on the axis of rotation of the projectile.

A further object is to provide a driving weight for a device of the character which exerts a constant torque on the driven parts.

A further object is to provide a delay arming device including a rotor, a primer carried by the rotor, and means for holding said rotor immobile with the primer in a disarmed position until the completion of the delay cycle and means thereupon operative to release said rotor for movement to position said primer in an armed position.

A further object is to provide a delay arming device such as that last described which includes swingable means engaging said rotor to prevent rotation thereof, latch means engaging said rotor to prevent rotation and a portion of said swingable means normally engaging said latch to prevent release of the same from said rotor until the end of the arming cycle, said swingable means being operative to relieve said latch from torque pressure of said rotor during the arming cycle.

A further object is to provide a delay arming device including mechanism for moving a primer into an armed position at the close of an arming cycle, a cover plate having an aperture therethrough for passage of a firing pin, and overlapping movable portions of said mechanism closing said hole at all times prior to the arming of said device.

Other objects and advantages reside in the particular form of the invention, in the combination and arrangement of the several parts thereof and in the particular method or mode of operation, all of which will be readily apparent to those skilled in the art upon reference to the drawing and specification wherein the invention is shown, described and claimed.

In the drawing:

2

Figure 1 is a plan view of one form of the invention showing the cover plate in position and the parts in the unarmed position.

Figure 2 is a view like Figure 1 with the cover plate removed.

Figure 3 is a view like Figure 2 but showing the parts in the armed position.

Figure 4 is a vertical section on the plane of the line 4—4 of Figure 2.

Figure 5 is a horizontal section taken on the plane of the line 5—5 of Figure 4.

Figure 6 is a horizontal section taken on the plane of the line 6—6 of Figure 4.

Figure 7 is a view like Figure 2 but showing a modification of the invention.

Figure 8 is a view like Figure 7 but showing the parts in the armed position; and

Figure 9 is a fragmentary vertical section taken on the plane of line 9—9 of Figure 7.

20 Referring specifically to Figs. 1—6 inclusive, 10 designates a casing for one form of our invention. Such casing is of cup-like form and the open end thereof is internally and externally threaded at 11 and 12 for engagement with the fuse and shell respectively, not shown. Below the internal threads 11, the casing 10 is formed with a reduced and irregular recess 13 which provides at its upper edge a shoulder 14 for the cover plate 15. The cover plate 15 is centrally apertured at 16 for the passage of the firing pin, not shown, and is further provided with a plurality of irregularly disposed holes to receive positioning pins, pivot pins and the like including fastening means 17.

35 The delay arming mechanism is seated in various parts of the recess 13 and comprises a rotor 20, a latch 30, a weighted driving lever 40 and a swingable gear train assembly 50, all of which will be described in detail hereinafter.

40 Rotor 20 is pivoted at 21 eccentric to the axis of casing 10 and is formed with an arm 22 through which is formed an aperture seating a primer 23. Opposite the arm 22, the rotor 20 is formed to provide a fan-shaped eccentric weight 24 whereby centrifugal force generated by the rotation of the shell after firing tends to rotate the rotor in a counterclockwise direction. A portion of the upper surface of the weight 24 is cut away to provide a recess 25 to receive 45 and confine the free end of the swingable gear train assembly 50 when the mechanism is in the unarmed position (Fig. 2). A marginal edge of the recess 25 is formed to provide a notch 26 to receive the inner dog 33 of the latch 30 and 50 is further recessed to provide a bevelled shoul-

der 27 to seat the weighted driving lever 40. A stop pin 28 is provided in the cavity 13 to limit the movement of the rotor in both directions. When the rotor is in the unarmed position, the primer 23 is positioned out of alignment with the flame hole 29 which extends through the floor of and is located on the axis of the casing 10. When the rotor is in the armed position, the primer is aligned with such flame hole.

The latch 30 comprises a generally arcuate centrifugally actuated lever one end of which is pivoted to the casing 10 at 31. A weight 32 is formed on the upper surface of the latch 30 adjacent the free end thereof and serves the dual purpose of accentuating the centrifugal force actuating the lever and also serves as an auxiliary support for the gear assembly 50 during setback. (Fig. 4.) The free end of the latch lever 30 is formed to provide inner and outer dogs 33 and 34 respectively. The inner dog 33 is adapted to seat in the notch 26 of the rotor 20 when the latter is in the unarmed position to prevent rotation thereof. The outer dog 34 bears against the rounded portion of the pivot 51 of the gear assembly 50 to maintain the latch in locking relation to the notch 26 of the rotor 20. When the pivot shaft 51 has been rotated a predetermined distance, as will be described later, the flat portion 52 clears the dog 34 and permits centrifugal force to swing the latch radially outward to release the dog 33 from the notch 26 of the rotor 20.

The driving lever 40 is generally arcuate in form and is pivoted at one end as at 41 to the casing 10. A driving weight 42 is formed on the driving lever adjacent the free end thereof for accentuating the centrifugal force generated by the rotation of the shell in flight and which causes the driving lever to swing radially outward. The free end of the driving lever is formed to provide a segmental gear 43. When the driving lever 40 is in the unarmed position (Figs. 2 and 6), it bears against the bevelled shoulder 27 of the rotor 20 and the radially outermost of the teeth of gear 43 are in driving engagement with a pinion 53 of the pivotal shaft 51 of the gear train assembly 50. Thus, as the driving lever 40 is swung outwardly by centrifugal force, the segmental gear 43 rotates the pinion 52 and the pivotal shaft 51.

The gear train assembly case 50 comprises a generally arcuate casing one end of which is pivotally connected to the casing 10 by the pivotal shaft 51. The gear case 50 contains any suitable reduction gearing which is adapted to be driven by rotation of shaft 51 and which drives an escape wheel 54 rotation of which is regulated by an escapement 55 (Figs. 1, 2, 3). For the purpose of clarity, the gear train within the case 50 has not been shown as no particular reduction gearing is claimed herein. When the gear case is in the unarmed position (Figs. 1, 2), the free end bears against a side wall of the recess 25 of the rotor 20 so as to assist in preventing rotation thereof and to relieve the latch dog 33 of part of the torque pressure of the rotor 20. With the gear case 50 in the unarmed position (Figs. 2 and 4), the free end thereof is positioned in alignment with the flame hole 29 of the casing 10 and forms an added safeguard against premature detonation of the shell. The escapement 55 is then positioned, as shown, on the axis of rotation of the casing 10.

In operation, when the shell is fired a rapid rotation is imparted thereto by the lands and grooves of the gun barrel. Such rotation gener-

ates a centrifugal torque in each of the parts 20, 30, 40 and 50, but the parts 20, 30 and 50 are temporarily prevented from reacting to such torque by the various latching devices. However, the driving lever 40 is not latched and immediately commences to swing in a clockwise direction on its pivot 41. At the same time the segmental gear 43 of drive lever 40 begins to rotate the pinion 53, shaft 51, and the reduction gears contained in the case 50. The case 50 remains stationary as it is confined in the recess 25 of rotor 20. The length of time, and the consequent delay in the arming time, consumed in the passage of the segmental gear 43 past the pinion 53 depends upon the number of teeth on said gears and the particular arrangement of speed reduction gears in the case 50 and is unimportant for the purposes of this invention. However, it is important that the segmental gear 43 clear the pinion immediately after the positioning of the flattened part 52 of shaft 51 at a point to clear the outer dog 34 of the latch 30, whereby centrifugal force swings the latch 30 out of engagement with the rotor notch 26 just before the segmental gear 43 clears the pinion 53 and frees the gear case 50 for centrifugally actuated swinging movement out of engagement with the shoulder of the recess 25 of the rotor 20. Centrifugal force thereafter causes the rotor 20 to swing in a counterclockwise direction until stopped by stop pin 28, at which position the primer 23 is aligned with the flame hole 29 and the mechanism is armed. Centrifugal force thereafter maintains the parts in the armed position. In the event that it is found to be desirable to incorporate positive means for maintaining the parts in the armed position, any well known automatic means (not shown) for accomplishing this purpose may be incorporated into the device.

The modification of Figs. 7, 8, 9, is generally similar to the form of the invention of Figs. 1-6 inclusive, and comprises a casing 100 having a flame hole 129 extending axially thereof through the floor of an irregular recess 113 therein. As in the first described form of the invention the delay mechanism comprises a rotor 120, latch 130, driving lever 140 and reduction gear case 150.

The rotor 120 is pivotally mounted at 121 for rotation in the recess 113 and mounts the primer 123. A recess 125 is formed in the upper surface of the weighted end 124 of the rotor and provides an abutment 127 at one side thereof which seats the free end of the gear case 150 when the parts are in the unarmed position (Fig. 7). A marginal edge of the recess 125 is formed to provide a notch 126 to receive the latch dog 133 of the latch 130.

The latch 130 is pivoted to the casing 100 at 131 and is provided at its free end with the latch dog 133 on the inner edge thereof. The outer edge 134 of the free end of the latch is concave in form and concentrically engages the circular edge of a latch disc 156 which is fixed on the pivot shaft 151 of the gear case 150. Such engagement of the disc 156 and the latch 130 maintains the latter in latching engagement with the rotor 120.

The driving lever 140 is pivoted to the casing 100 at 141 and the free end thereof is formed to provide a segmental gear 143 which, in the unarmed position is in engagement with the pinion 153 of the gear case 150. Suitable weights (not shown) may be added to latch 130 and driving

lever 140 to correspond to weights 32 and 42 of the first described form of the invention.

The gear case 150 is pivoted to the casing 100 by the pivot shaft 151 as aforesaid, and comprises upper and lower plates 158 held apart by spacers 159 and mounting any suitable reduction gear train 157 which is adapted to be driven by rotation of the pivot shaft 151 and which is regulated by the escape wheel 154 and escapement 155. The latch disc 156 is fixed on shaft 151 and is cut away at one side to provide a concave recess 152. The curve defining such recess 152 substantially corresponds to the arc described by the free end of the latch 130 whereby to permit disengagement of the latter from the rotor 120 when rotation of the shaft 151 has progressed sufficiently to position an initial portion of said recess 152 in alignment with the free end edge of such latch. As in the first described form of the invention, this event occurs just before the segmental gear 143 clears the drive pinion 153 so that the bearing of the free end of the gear case 150 against the abutment 127 of the rotor is maintained for a split second after the latch disengages to facilitate the latter operation.

It should be noted that in both forms of the invention, the torque generated in the gear cases 50 and 150 by the rotation of the drive pinions 53 and 153 is in a direction to urge the free ends of the gear cases in directions to resist the torque of the rotors.

The structures of both forms of the invention have similar advantages which include a driving lever exerting a constant torque; the escapements positioned on the axis of rotation of the shell whereby the centrifugal force generated in flight exerts little or no force on the escapement during the operation of the delay mechanism; the rotors are retained in the unarmed position until the arming points are reached by the combined locking functions of the latch and gear case; and the swingable feature of the gear case enables it to close the firing pin opening 16 in the cover plate 15 until the arming point is reached, thereby providing an additional safeguard against premature detonation. It should be noted also, that in both forms of the invention the shape of the recesses 25 and 125 in the rotor is such that they confine the free end of the gear cases therein to prevent premature or accidental swinging of the same to the armed position.

While we have shown and described what are now thought to be the preferred forms of our invention, it is to be understood that the same is susceptible of other forms and expressions. Consequently, we do not limit ourselves to the precise structures shown and described except as hereinafter claimed.

We claim:

1. A delay arming mechanism for a projectile, comprising a casing, having an axial flame hole therethrough, a rotor eccentrically mounted in said casing for centrifugally actuated movement from an unarmed to an armed position, a latch pivotally mounted in said casing and engageable with said rotor for locking the same in an unarmed position, a gear case including a drive pinion, a gear train driven thereby and an escapement regulating said drive, said gear case being swingably mounted in said casing for centrifugally actuated movement from an unarmed to an armed position, said escapement being positioned on the axis of rotation of said casing in the unarmed position, a recess in said rotor receiving said gear case in the unarmed position and hold-

ing the same in said position, a centrifugally actuated drive lever pivotally mounted in said casing and including a segmental gear on the free end thereof in working engagement with said drive pinion when the mechanism is in the unarmed position, said segmental gear being operative to rotate said pinion and actuate said gear train upon swinging of said drive lever, means associated with said pinion and engaging said latch to hold the same in latching relation to said rotor throughout the greater portion of the rotation of said pinion and thereafter releasing said latch for disengagement from said rotor, said segmental gear thereafter clearing said pinion to release said gear case for centrifugally actuated movement out of engagement with said rotor to permit centrifugally actuated movement of said rotor to the armed position.

2. The structure of claim 1, a pivot shaft pivotally mounted in said casing and having said pinion fixed thereon, said shaft being notched at one side thereof, said shaft comprising said means engaging said latch, and said notched portion being adapted to register with said latch upon partial rotation of said shaft to release said latch for disengagement from said rotor.

3. The structure of claim 1, a pivot shaft mounting said pinion, said shaft being pivotally mounted in said casing, a disc fixed on said shaft adjacent said pinion, a concave recess in one edge of said disc, the rounded portion of said disc comprising said means engaging said latch, and said concave recess being adapted to register with said latch upon partial rotation of said shaft to release said latch for disengagement from said rotor.

4. A delay arming mechanism for a projectile, comprising a casing, an axial flame hole therethrough, primer means mounted in said casing for centrifugally actuated movement from an unarmed position to an armed position in alignment with said flame hole, a gear case pivotally mounted in said casing, a delay arming gear train and an escapement in said gear case, centrifugally operated means for actuating said gear train, said escapement being positioned over and across said flame hole when in unarmed position to close said flame hole, said gear case being pivoted to clear said flame hole upon completion of the arming cycle.

5. A centrifugally operated delay arming mechanism for a projectile, comprising a casing, a primer carrying rotor pivoted in said casing, a pivoted latch for locking said rotor in an unarmed position, a pivotally mounted delay gear train in said casing and including means engaging said latch to hold the same in a latching position during the arming cycle, means on said rotor engaging said gear train to hold the same in an unarmed position during the arming cycle, and centrifugally actuated means for actuating said gear train to provide the arming cycle and to release successively said latch, rotor and gear train for centrifugally actuated movement to armed positions at the completion of said arming cycle.

6. The structure of claim 5, an escapement on said gear train, and said escapement being positioned on the axis of rotation of said projectile during the arming cycle.

7. In a centrifugally operated delay arming mechanism for a projectile, a generally cylindrical casing having a first central axis of rotation, a centrifugally operated rotor pivoted in said casing on a second axis radially offset in one

direction from said central axis, a gear case, an escapement and gear drive therefor in said gear case, means journaling said gear case in said casing for pivotal movement as a unit on a third axis radially offset from said central axis in a direction opposite to said one direction, centrifugally operated means for driving said gear train and escapement in response to rotation of said mechanism on said central axis, latch means normally holding said rotor and gear case in unarmed inwardly-pivoted positions, and means responsive to driving of said escapement for releasing said latch means to free said rotor and gear case, said rotor and gear case then pivoting outwardly away from said central axis in generally opposite directions.

8. In a centrifugally operated delay arming mechanism for a projectile, a casing having an end wall, a central axis of rotation and a flame hole in said wall, a gear case pivoted in said casing on an axis offset from said central axis, a gear train and escapement carried by said gear case, latch means normally holding said gear case in an unarmed position over said hole, means centrifugally responsive to rotation of said mechanism about said central axis to drive said gear train and escapement, and means responsive to a predetermined operation of said gear train and escapement to release said latch means and permit centrifugal movement of said gear case to an armed position clear of said hole.

9. A centrifugally operated delay arming mechanism for a projectile comprising a casing having a central axis of rotation, a closed end wall and a flame hole through said wall, an escapement and driving gear assembly pivoted in said casing for movement as a unit about an axis offset from said central axis, holding means including a centrifugally operated latch for holding said assembly in unarmed position closing said hole, means responsive to centrifugal force created by rotation of said mechanism on said central axis for driving said gear and escapement assembly, and means responsive to a predetermined operation of said escapement to release said holding means and permit centrifugal pivotal movement of said assembly to armed position clear of said hole.

10. A mechanism as recited in claim 9, said holding means including a rotor journaled in said casing and having a primer moved into alignment with said hole as said rotor pivots from a first unarmed position to a second armed posi-

tion, there being a recess in the periphery of said rotor in which the free end of said assembly fits when said assembly and rotor are in their respective unarmed positions.

- 5 11. In a centrifugally operated delay arming mechanism for a projectile, a casing having a closed end, a central axis of rotation and a flame hole in said end substantially on said axis, a rotor pivoted in said casing on an axis radially offset in one direction from said central axis, an escapement and driving gear assembly pivoted in said casing on an axis radially offset in the opposite direction, said rotor and assembly when in unarmed position being superposed over said hole, latch means holding said rotor and assembly in unarmed position, means responsive to rotation of said mechanism for driving said escapement, and means responsive to a predetermined degree of driving of said escapement to release said latch means whereby said rotor and assembly are pivoted radially outward in opposite directions to arm said mechanism.
- 10 12. In a centrifugally operated delay arming mechanism for a projectile, a casing having an end wall, a central axis of rotation and a flame hole in said wall in substantial alignment with said central axis, a gear case pivoted in said casing on an axis offset from said central axis, a gear train and escapement carried by said gear case, latch means normally holding said gear case in a first position over said hole, centrifugally-operated means to drive said gear train and escapement, and means responsive to a predetermined operation of said gear train and escapement to release said latch means and release said gear case for movement to an armed position clear of said flame hole.
- 15 13. The mechanism recited in claim 12, said escapement being substantially on said central axis when said gear case is in unarmed position.
